(57) **CLAIM**

The ornamental design for a light-emitting therapeutic device, as shown and described.

DESCRIPTION

FIG. 1 is a rear view of a light-emitting therapeutic device; FIG. 2 is a front view of the light-emitting therapeutic device of FIG. 1;

FIG. 3 is a right side view of the light-emitting therapeutic device of FIG. 1, the left side view being a mirror image of the right side view;

FIG. 4 is a top view of the light-emitting therapeutic device of FIG. 1;

FIG. 5 is a bottom view of the light-emitting therapeutic device of FIG. 1;

FIG. 6 is a rear perspective view of the light-emitting therapeutic device of FIG. 1; and,

FIG. 7 is a front perspective view of the light-emitting therapeutic device of FIG. 1.

The broken lines shown in the drawings represent unclaimed portions of the design and form no part thereof.
